HOWARD G. LAPSLEY, OF PLAINFIELD, NEW JERSEY.

SNOW-MELTING DEVICE.

1,073,427.

Specification of Letters Patent. Patented Sept. 16, 1913.

Application filed April 22, 1911. Serial No. 622,791.

To all whom it may concern:

Be it known that I, HOWARD G. LAPSLEY, a citizen of the United States, residing at Plainfield, in the county of Union and State 5 of New Jersey, have invented certain new and useful Improvements in Snow-Melting Devices, of which the following is a specification.

This invention relates to snow melting devices; and it comprises a transportable casing, advantageously wheeled, having a perforated false bottom, means for removing water therebeneath, a removable top carrying a slidably mounted steam pipe terminating in a rose or the like and adapted for connection with a source of steam, and sealing means for said top; all as more fully hereinafter set forth and as claimed.

It is often desirable to melt snow as a 10 quick and easy method of removing it. The amount of heat required for melting snow is relatively great, and the specific heat of the water formed is also relatively great so that in this operation an economy of heat 15 is very desirable; and it is desirable that the apparatus to be employed shall give this economy. Various devices have been proposed for melting by the aid of fire heat applied in one way or another, but the utilization 20 of heat in this manner is not good. It is better to use steam, either exhaust or direct steam as the case may be. In melting by steam, it is desirable that the steam be confined in contact with the snow until the 25 melting is effected and the temperature of the whole system of steam and snow becomes, as nearly as possible, 32° F. And it is desirable that the water be removed as 30 fast as formed in order to avoid unnecessary expenditure of heat by delivering the water 35 at a temperature above 32° F.

In the present invention I have devised a simple, cheap and economical apparatus for melting snow by the use of steam. For this 40 purpose I provide a transportable casing or container, which is advantageously mounted on cart wheels and may be made of metal or other suitable material. Within this container I provide a perforated false bottom 45 upon which the snow may rest. Below the perforated false bottom I provide a valved outlet or other suitable means for removing water trickling through such bottom so that water may not remain in the presence of the 50 heating agent but may escape at the temperature at which it is formed, 32° F. I

provide a removable top for this container with gasketing means to make it substantially air tight and steam tight in use. The gasketing means do not have to resist any 60 pressure since the steam introduced is at once condensed by the snow and consequently no pressure is produced. Through a gland or stuffing box in this top I pass a 65 slidably mounted steam pipe provided with a valve near its top and with a rose or the like at its bottom. The steam pipe may be provided with a hose or other suitable means for forming connection with a pipe supplying either live or exhaust steam. The 70 container may be filled with snow at any place desired and wheeled into proximity to the source of steam, the top applied, connection made with said source, and the rose at the 75 end of the steam pipe pushed down to the bottom of the snow. On now passing in steam the rose distributes it in fine jets within the lowermost layer of snow, quickly melting it. Any steam escaping immediate condensation and rising, is at once condensed 80 by the snow above. The water formed passes downward and escapes through the perforated bottom at the temperature of melting, 32° F. Water and snow can only co-exist at 32° F. As the snow disappears 85 the steam pipe is raised upward. The steam being introduced into direct contact with the snow, and there being snow above the point of introduction, no steam accumulates in the chamber above the snow. 90

In the accompanying illustration I have shown, more or less diagrammatically, an advantageous embodiment of the described invention.

In this showing, Figure 1 is an elevation 95 of the cover and attachments; and Fig. 2 is an elevation, partly broken away, of the mounted body of the snow melter, without the cover.

Referring to the drawings, 1 is a snow 100 container mounted on wheels 2 and provided with handles 3. Within the container near its bottom is a perforated false bottom 4, forming a chamber 5 for water therebelow. Valved outlet 6 permits withdrawal of the 105 water and discharge into a sewer or the like. Top 7 (shown above the container for convenience of illustration) is of a form adapting it to fit the rim of the container and is provided with gasketing means 8 and with 110 flanges 9 and 10, allowing a tight joint to be readily made. Handles 11 allow con-

venient manipulation. Through gland 12 in the top passes a steam pipe 13 provided with valve 14 and connecting means 15, shown as a piece of rubber tubing. At its 5 base the pipe is provided with rose 16.

The use of the above structure is evident from the foregoing. Container 1 is filled with snow at any desired point and wheeled into proximity to a source of steam. Top 7 10 is then placed in position, 8, 9 and 10 allowing an air tight union to be readily made. Hose 15 is connected to a steam pipe, valve 14 opened, and pipe 13 pushed through the snow to a point near the perforated false 15 bottom. The steam flowing from the rose melts the snow rapidly enabling the steam pipe to be readily forced down to the false bottom.

The container may be a can of about a 20 cubic yard capacity and may be of the general shape of a truncated cone.

While the snow as it melts, may tumble more or less, it generally preserves an arched form and the rose is kept in this 25 arch by the progressive upward pulling of the pipe 13 through the gland or stuffing box 12. The perforated false bottom acts as a trash-catcher, preventing sticks, stones, and other rubbish unavoidably collected 30 with the snow from passing into the sewer or other place of discharge.

What I claim is:—

1. In a snow melting device, a transportable casing provided with drainage means 35 near its base, a removable top for the casing

provided with means for making a tight joint and a steam pipe passing through and vertically movable with relation to said top and provided with steam distributing means at its lower end. 40

2. In a snow melting device, a transportable casing, a false bottom spanning it near the base, a removable top therefor provided with means for making a tight joint, and a steam pipe passing through and vertically 45 movable with relation to said top and provided with steam distributing means at its lower end.

3. In a snow melting device, a wheeled casing, a false bottom spanning said container near the base, means for removing water therebelow, a removable gasketed top carrying a gland, and a valved, vertically movable steam pipe passing through said gland and provided with a rose at its lower 55 end. 50

4. In a snow melting device, a transportable casing with a false bottom near the base and means for removing water therebelow, a removable top therefor provided with 60 means for making a tight joint and a steam pipe passing through said top and provided with steam distributing means at its lower end.

In testimony whereof, I affix my signature in the presence of witnesses.

HOWARD G. LAPSLEY.
